UNITED STATES PATENT OFFICE.

JONATHAN A. HUNT, OF SALEM, MASSACHUSETTS.

NEEDLE FOR SOUND-REPRODUCING MACHINES.

1,312,849.

Specification of Letters Patent.

Patented Aug. 12, 1919.

Application filed March 28, 1918. Serial No. 225,225.

To all whom it may concern:

Be it known that I, JONATHAN A. HUNT, a citizen of the United States, residing at Salem, in the county of Essex and State of 5 Massachusetts, have invented certain new and useful Improvements in Needles for Sound-Reproducing Machines, of which the following is a specification.

My invention relates to a needle for sound 10 reproducing machines.

The object of my invention is to provide an improved needle for sound reproducing machines, which will give better results than the needles now ordinarily used.

15 My invention consists in certain novel features of construction of my improved needle for sound reproducing machines, as will be hereinafter fully described.

Referring to the drawing:—

20 Fig. 1 is a side elevation of a sound reproducing sound box, and a sectional view of a sound record disk, and shows my improved needle in operable position.

Fig. 2 shows, on an enlarged scale, the 25 needle shown in Fig. 1, detached.

Fig. 3 is a section, on line 3, 3, Fig. 2, looking in the direction of the arrow, same figure.

Fig. 4 shows a modified construction of 30 the needle shown in Fig. 3.

Fig. 5 shows another modified construction.

Fig. 6 shows another modified construction.

35 Fig. 7 shows another modified construction.

Fig. 8 shows another modified construction.

Fig. 9 shows another modified construction.

Fig. 10 shows another modified construction, and

Fig. 11 shows another modified construction.

45 In the accompanying drawing, 1 is a sound reproducing sound box, which may be of any ordinary construction, and such as is used in connection with sound reproducing machines which use flat disk records.

50 2 is the needle holding socket of the sound box, and 3 the clamp screw, which acts to engage and hold the needle 4 in place in the socket 2. 5 is a detached sectional portion of the flat disk or record, 55 which has the groove 5' in the upper face

thereof, into which the point 4' of the needle 4 extends.

I will now describe my improvements in needles.

As stated above, the object of my invention is to provide a needle which will give better results than the needles now ordinarily used. My improved needle is preferably made of metal, and is preferably of diamond, or oval shape in cross section for 60 a portion, or the whole of its length, and preferably has both ends cut diagonally or inclined, to form a sharp point to enter the groove in the disk.

If preferred, one or both ends may be 70 square across, or of a shape to furnish four corners or points for playing.

I have shown in Figs. 2, and 3, the preferred form of my improved needle 4, which is of diamond shape in cross section, with 75 two flattened portions or surfaces 4'', one on each side of the needle, against one of which the inner end of the set screw 3 bears when the needle is in position, as shown in Fig. 1.

80 In Fig. 2, the needle 4 is shown on an enlarged scale, with each end of diagonal shape and forming a sharp point 4'. The inclined portion of each end is on opposite sides or edges of the needle, so that in cutting up the strip, from which the needles are made, there is no waste of material, and one operation of cutting the strip, makes the two operating ends on two needles, thus reducing the cost of production. 85

90 By this construction, each needle has a playing point at each end, one point on one edge, and the other point on the opposite edge.

Fig. 4 shows a modified construction of the 95 needle shown in Fig. 3, having only one side flattened.

Fig. 5 shows another modified construction, in which the needle is of a greater thickness, with one side slightly flattened.

100 Fig. 6 shows another modified construction, in which the needle is of still greater thickness, with one side flattened.

Fig. 7 shows another modified construction, in which the needle is of oval shape in 105 cross section, with flattened sides.

Fig. 8 shows another modified construction, in which the needle is of oval shape with curved sides.

Fig. 9 shows another modified construc-

110

tion, in which the needle is of oval shape and of less diameter, and

Fig. 10 shows another modified construction, in which the needle is of oval shape, 5 and of still less diameter.

Fig. 11 shows another modified construction, in which the needle is of square shape in cross section.

The needles of different shapes in cross 10 section, shown in Figs. 4 to 11 inclusive, produce an entirely new line of tones from the sound reproducing disk.

It will be understood that the details of construction of my improved needle may be 15 varied if desired, and it is intended to be used in any kind of sound reproducing machine.

If preferred, the portion of the needle intermediate the ends may be round, or of 20 other shape in cross section. The needle may be of square shape in cross section, throughout its length, or near each end.

Having thus described my invention, what 25 I claim as new and desire to secure by Letters Patent is:

1. A needle for sound reproducing machines, the lateral surface of which has two edges situated at opposite ends of the longest dimension of the cross section, said needle 30 having a flattened surface parallel to the plane of said edges and extending the whole length of the needle.

2. A needle for sound reproducing machines, the lateral surface of which has two 35 edges situated at opposite ends of the longest dimension of the cross section, said needle having a flattened surface parallel to the plane of said edges and extending the whole length of the needle, the end surfaces of 40 said needle being planes perpendicular to said flattened surface and oblique to the axis of the needle.

3. A needle for sound reproducing machines wherein the lateral surface has two edges located diametrically opposite one another, the ends of the needle being parallel planes whereby the needle has a playing point at each end, one point on one edge, and the other point on the other edge. 45

4. A needle for sound reproducing machines wherein the area of the cross section is reduced by flattening one side of the needle, the flattened surface extending throughout the length of the needle, the playing point being outside of the plane of 55 the flattened surface whereby the orientation of the needle in the machine and the tone of the needle are controlled.

5. A needle for sound reproducing machines having a cross section with two diametrically opposite vertices, the ends of the needle being parallel planes whereby said needle has two working points situated at opposite ends, and in diametrically opposite elements of the lateral surface. 60

6. A needle for sound reproducing machines having a cross section, one diameter of which is longer than the others, the cross section being symmetrical about the diameter at right angles to said longest diameter, 70 said needle having two working points located in elements of the lateral surface at ends of the longest diameter.

7. A needle for sound reproducing machines of non-circular cross section, said needle having two working points, one located at the end of one element of the lateral surface, and the other located at the end of the diametrically opposite element of the lateral surface at the other end of the needle. 80
